UNITED STATES PATENT OFFICE

ROBERT H. BEAUMONT, OF RADNOR, PENNSYLVANIA, ASSIGNOR TO R. H. BEAUMONT COMPANY, OF PHILADELPHIA, PENNSYLVANIA, A CORPORATION OF PENNSYLVANIA

OUTLET APPARATUS FOR ASH BUNKERS

Application filed October 21, 1927. Serial No. 227,679.

Objects of the present invention are to provide outlet apparatus for ash bunkers such as are arranged under boilers and discharge into water sluices or other conveyors, which will entirely close the outlet and thus prevent air from entering the furnace by way of that outlet, which will feed ashes and clinker, and which will crush clinkers of considerable size.

Other objects of the invention will appear from the following description but it may be said that the invention, generally stated, comprises outlet apparatus for ash bunkers including a frame and a plate horizontally reciprocatable in respect to the frame and adapted to operate as a gate and a feeder and a clinker crusher.

The invention also comprises the improvements to be presently described and finally claimed.

20 In the following description reference will be made to the accompanying drawings forming part hereof and in which

Figure 1 is an elevational view partly in section and partly in elevation illustrating 25 ash hoppers provided with outlet apparatus embodying features of the invention and showing also a part of an ash bunker.

Fig. 2 is a view in part a transverse section taken on the line 2—2 of Fig. 1.

30 Fig. 3 is a sectional view taken on the line 3—3 of Fig. 2.

Fig. 4 is an end view partly in section similar to Fig. 2 and illustrating a modification, and

35 Fig. 5 is a detail sectional view illustrating a modification of the clinker crusher shown at the righthand lower portion of Fig. 2.

Referring more particularly to Figs. 1 to 40 3, 1 is a plate mounted for horizontal reciprocation. Referring to Fig. 2 the left-hand portion of this plate 1 always underlies the discharge opening 2 at one side of the apex of the hopper 3 of the bunker 4. The righthand portion of the plate 1 covers 45 and uncovers the inlet opening 5 to a conveyor which happens to be shown in the form of a sluice 6, which, however, is merely typical. There is a frame 7 with which the end 8, shown as beveled to an edge, of the plate 1 cooperates. 10 is an enclosure on both sides

and at the top of the plate 1 and at one end it is in open communication with the outlet 2, and at the other end it is upwardly inclined as at 11 and provided with an upwardly opening normally closed door 12, 55 hinged at 13.

The mode of operation may be described as follows:

When the plate 1 is in reciprocation it continually feeds ashes and clinker from the 60 hopper to the inlet 5 of the conveyor. Ashes and small clinker drop through the opening 5. Larger clinkers are crushed between the end 8 of the plate and the frame 7 to pieces of such size that they fall through the 65 opening 5, and still larger clinkers, under the feeding action of the plate 1, are pushed up the incline 11 and opening the door 12 give notice that their removal is required. Obviously the rate of ash feed to the 70 conveyor may be adjusted and thereafter kept constant by changing the speed of the plate 1, by changing the throw of the plate 1 in respect to the frame 7, and by adjusting the position of the throat plate 24, or by a combination of these. The adjustment of throat plate 24 may be made by loosening the unnumbered bolts which hold the throat plate 24 to the incline 11 and moving the bolts in slots (not shown in the drawings as the 75 scale is too small) which may be provided in the plate or in the incline or in both. Another method of adjustment is to remove the throat plate 24 and to substitute another of different size. 85

When it is not desired to remove ashes and clinker the plate 1 in cooperation with the frame 7 serves to close the inlet 5 preventing the entrance of air.

It is an advantage that the rate of feed 90 to the conveyor may be proportioned to its capacity and it is an advantage of the structure that it takes up very little head room, and since apparatus of this type is usually located in basements and the like under boilers, the matter of head room is important.

A car 14 arranged to travel on tracks aligned with a series of hoppers and provided with a pitman mechanism 15 is a means 95 for operating a series of the described plates 100

1. The rod 16 of the pitman mechanism is arranged as indicated at 17 for detachable connection with the plates 1, so that the car may travel along and be connected with the 5 plates of the series so as to reciprocate them one at a time. When at rest the plates 1 are in position to close the outlets 5. The pin and slot connection 18 are a means for varying the throw of the plates 1, and the motor 10 on the car is a means for varying the speed of reciprocation of the plates 1.

The construction and mode of operation of the modification shown in Fig. 4 are as above described except that the car 19 carries the 15 reciprocating plate 1, the frame 7, the housing 10, and the pitman mechanism 20. Each hopper 21 is provided with a gate 22 and the outlet to the conveyor is provided with a lid 23. When the outlet apparatus is in 20 position under a hopper 21, the lids 22 and 23 are open so that the hopper discharges into the enclosure 10 and onto the plate 1, but when the outlet apparatus is not under a hopper, its gates 22 and 23 are closed.

25 In order to permit the device to crush large lumps down to predetermined size use may be made of an inclined crushing throat 8' and 24' in association with the plate 1' however reciprocated horizontally.

30 It will be obvious to those skilled in the art to which the invention relates that modifications may be made in details of construction and arrangement and matters of mere form without departing from the spirit of the invention which is not limited to such matters or 25 otherwise than the prior art and the appended claims may require.

I claim:

1. Outlet apparatus for ash bunkers comprising a hood open at one end for the reception of ashes and clinker and having at its other end an upwardly and outwardly inclined portion and an outwardly opening door, said hood having near the closed end 45 a frame providing an outlet, and a plate reciprocatably mounted across said outlet at the lower portion of the hood and adapted to operate as a gate and a feeder and a clinker crusher.

50 2. In combination an ash bunker having an outlet, a conveyor having an inlet arranged to one side of the outlet, a horizontally reciprocating plate of which one edge portion underlies the opening in all positions of the 55 plate and of which the other edge portion covers and uncovers the conveyor inlet, an air-tight enclosure enclosing the plate, said plate acting in cooperation with the enclosure as a gate and a feeder and in cooperation with 60 the wall of the inlet which confronts its end as a clinker crusher.

3. Outlet apparatus for ash bunkers including a hopper having an outlet adjacent its bottom, a frame of which a part underlies 65 said outlet and of which the remainder ex-

tends laterally away and surrounds a conveyor opening spaced from beneath said opening in said hopper, a plate received in said frame and underlying said opening in said hopper and overlying said conveyor opening and horizontally reciprocatable in respect to the frame to provide a gate for material in said hopper by holding said material in the opening in said hopper and to feed material from said opening in said hopper to said conveyor opening and to cooperate with a portion of said frame to crush material therebetween, and an air-tight hood surrounding and enclosing the opening in said hopper and said plate and said conveyor opening to prevent the escape of dust from the material thereon. 70

4. Outlet apparatus for ash bunkers including an air-tight hood adapted to receive ashes and to deliver the same and to prevent the escape of dust from said ashes during said reception and delivery, a plate reciprocatably mounted at the bottom of said hood and adapted to operate as a gate by holding ashes in a pile on entering said hood and to operate as a feeder by conveying the ashes through said hood and to operate as a clinker crusher by pressing at one end on clinkers, and a frame surrounding said plate and having an adjustable throat piece opposite the end of said plate to cooperate therewith to crush 95 clinkers therebetween. 80
